UNITED STATES PATENT OFFICE.

DAVID ROSEN, OF PHILADELPHIA, PENNSYLVANIA.

GROUND CONNECTION FOR ELECTRICAL CONDUCTORS.

1,171,142.

Specification of Letters Patent.

Patented Feb. 8, 1916.

Application fil. February 10, 1915. Serial No. 7,318.

To all whom it may concern:

Be it known that I, DAVID ROSEN, a subject of the Czar of Russia, residing at Philadelphia, in the county of Philadelphia and 5 State of Pennsylvania, have invented new and useful Improvements in Ground Connections for Electrical Conductors, of which the following is a specification.

This invention relates to certain new and 10 useful improvements in ground connections for electrical conductors, and pertains more particularly to that type of ground connection which is adaptable to connection with the pipes of water or gas systems employed 15 in dwellings and the like.

One of the objects of the invention is to provide a device of this character which, owing to its adjustability is readily adaptable to pipes of various sizes.

20 A further object of the invention is to provide a device which can be easily attached to and detached from pipes.

A further object of the invention is to provide a device of the above stated character which can be not only cheaply manufactured, but also possesses minimum of parts, thus facilitating assembling.

Referring to the drawings: Figure 1 is a perspective view of the device in place on 30 a pipe; Fig. 2 is a sectional view taken on the line 2--2 of Fig. 3; Fig. 3 is a sectional view taken on the line 3--3 of Fig. 2; and Fig. 4 is a face view of the blank.

Referring more particularly to the drawings, the numeral 1 designates a pipe employed in usual gas or water systems which pipes vary in size.

The numeral 2 designates a strip of flexible material such as copper, tin, or sheet 40 iron, one end of which is rolled over upon the body portion as shown at 3, and terminates in a free flat end portion 4 which lies in contact with the adjacent part of the body as best seen at 5 in Fig. 2 for a purpose to 45 be hereinafter described.

In proximity to the rolled over end 3 of the blank, is formed a perforation 5', while extending from a point substantially midway of the ends of the blank to the end opposite to the rolled over end 3 is a plurality 50 of perforations 6, 7, 8 and 9.

The body portion 2 is provided with a reinforcing member 10 in the form of a rectangular piece of stiff metal which is perforated and is rigidly secured to the part 5

of the body with its perforation in register with the perforation 5'.

Passing through the perforation 5' is a bolt 11 which has its head 12 in contact with the reinforcing member 10, and its free 60 screw-threaded end 13 engaged by a nut 15, the bolt being adapted to pass through any of the openings 6, 7, 8 or 9.

In use, the flexible metal band is bent to surround the pipe 1 as shown in Fig. 1, 65 whereupon the bolt 11 is inserted in the perforation 5', and its free end is passed through one of the perforations 6, 7, 8 or 9 according to the size of the pipe after which the nut 15 is threaded onto the end of the 70 bolt 11. It will be thus seen that upon tightening of the nut 15 the body portion of the metal strip which engages the pipe is caused to conform to the shape or contour thereof and owing to the presence of reinforcing member 10 the head 12 of the bolt is prevented from injuring or tearing the blank 2, and the latter is held stiff and rigid where reinforced by member 10.

By rolling over the end 3 of the blank 2 80 onto the body portion as shown at 4, it will be seen that the device not only provides a resilient clamp for the conductor wire 20, but one which will readily adapt itself to conductors of different diameters, since by 85 merely bending the part 4 toward or away from the part 5 small or large conductors can be readily accommodated, and in addition the eye which receives conductor 20 and which is formed by the rolled over part 3 90 can be bent up or down as desired.

It is to be particularly noted that the present invention can be easily and quickly applied to pipes of varying diameters and that the member 10 serves to bend the metal 95 into close engagement with the pipe upon tightening of the nut.

The part 4 provides an edge which can be readily lifted so as to remove the conductor and to also enable conductors of various 100 sizes to be placed within the eye.

What is claimed is:

As a new article of manufacture, a ground connection for electric conductors composed of a flexible strip bent to have its end portions lie in superposed relation, one of the horizontal end portions being slightly deflected downwardly and then rolled over to form a substantially circular conductor receiving eye, the free terminal of said end 110

portion being extended parallel with the latter to form a free flat liftable wing squarely seating on the strip, said liftable wing providing a means by which the eye may be 5 opened by inserting an instrument beneath said free flat wing, a relatively narrow strip-like block of a length approximately equal to the width of the strip rigidly secured to said end portion of the latter at a point in 10 wardly from the free side of the wing, and a bolt passed through said block and the end portions of the strip and having a nut thereon, said block providing an edge which

when the bolt is tightened causes the strip to be bent at said edge into engagement with 15 the pipe, said block also serving as a reinforcement for said specified end portion of the strip carrying said wing.

In testimony whereof I have hereunto set my hand in presence of two subscribing wit- 20 nesses.

DAVID ROSEN.
